UNITED STATES PATENT OFFICE

HAROLD E. COOMBS, OF GLENDALE, CALIFORNIA

DESIGN FOR A FLOWER STAND

Application filed June 9, 1931. Serial No. 40,142. Term of patent 14 years.

To all whom it may concern:

Be it known that I, HAROLD E. COOMBS, a citizen of the United States, and a resident of Glendale, in the county of Los Angeles and State of California, have invented a new, original, and ornamental Design for a Flower Stand, of which the following is a specification, reference being had to the accompanying drawing, forming a part thereof.

The figure in the drawing is a perspective view of the flower stand. My flower stand is symmetrical, and the sides opposite to those shown in the drawing are identical in appearance to the sides exposed.

I claim:

The ornamental design for a flower stand, as shown and described.

HAROLD E. COOMBS.
